NOISE INSULATING RING FOR EARPHONES

Filed Dec. 17, 1943

UNITED STATES PATENT OFFICE

2,447,470

NOISE INSULATING RING FOR EARPHONES

Joseph E. Valentine, Plainfield, N. J., assignor to
Oxxyn Company, Clifton, N. J., a corporation of
New Jersey

Application December 17, 1943, Serial No. 514,606

5 Claims. (Cl. 179—156)

1

This invention relates to an earphone assembly adapted to facilitate the reception of sound messages by an operator under conditions of noise and jarring such as are encountered, for example, in airplanes and tanks, and in many peace time operations as well as in warfare, which cause the hearing and accurate reception of phone messages transmitted by the ordinary earphone piece or receiver to be extremely difficult even when the ear piece is pressed so tightly against the operator's ear as to injure the cartilages of the ear.

An object of the invention is to provide a simple practical and effective assembly of the kind described.

Another object of the invention is to provide an earphone assembly with means adapted to form a noise excluding closure over and around the user's ear and the sound transmitting portion of said assembly.

Another object of the invention is to provide an assembly of the kind described, the parts of which, including a closure or support for known sound vibration translating means, are simple and easy to assemble and to disassemble.

Another object of the invention is to provide an earphone assembly with a sound excluding closure around the sound transmitting instrumentality thereof, having a portion adapted to serve as a bearing against the user's head, which bearing is so related to the said instrumentality and the carrier therefor that it is capable of swinging angular movement relative thereto.

Another object of the invention is to provide an earphone assembly which will be substantially non-responsive to externally induced vibrations.

Another object is in general to provide an improved apparatus of the above mentioned kind and a simple and efficient method of constructing the same. Other objects will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the accompanying drawings in which:

Figure 1 is a vertical cross sectional view, partly in elevation, of an earphone assembly em-

bodying my invention and its relation in use to the user's ear;

Figure 2 is a similar horizontal cross sectional view;

Figure 3 is a front elevation of the embodiment of the invention shown in Figures 1 and 2;

Figure 4 is a rear elevation showing a manner of detachably connecting the sound excluding closure to a carrier plate, and of connecting the assembly to a positioning headband; and

Figure 5 is a detail view, partly in section, through the ear and the holder for sound translating means.

Similar reference characters refer to similar parts throughout the drawings.

The carrier plate or backing 10 is preferably of a substantial size, and preferably circular and of a diameter on the order of the major axis of the ear. This carrier plate serves to support a holder 11 for sound translating means which in turn supports an ear plug adapted to fit in the user's ear and has a sound vibration conduit communicating with the sound translating means supported by said holder.

As illustrated the carrier 10 is annular having the central opening 10a in which the holder 11 is inserted and supported so that a portion of said holder, which may be apertured as at 12 to receive the telephone wiring 13, projects from one face of the carrier, and so that another portion of the holder 11 projects from the other face of the carrier and acts as a support for the ear plug 14, which may be frictionally engaged thereon.

Preferably the holder 11 is in the form of a two part closure the parts of which may be readily engaged and disengaged, and the engagement of which serves to secure the holder 11 in the aperture 10a of the carrier plate 10. Thus as illustrated herein the holder part 11a is cup-shaped and provided with a shoulder 15, adapted to abut against the rear face of carrier plate 10 and to position it against said plate, and it is externally threaded as at 16 for engagement with

the internal grooves 17 provided in holder part 11b, which may also be substantially cup-shaped, and has the outwardly projecting boss 18 through which a bore 19 extends thus communicating with the interior of the closure formed when the holder members 11a and 11b are assembled. It will thus be seen that when the holder member 11a is positioned in the aperture 10a of carrier plate 10, with its shoulder 15 in abutting relation to the carrier plate, and the holder member 11b is screwed onto the member 11a, so that the

threads of holder member 11a are seated in the grooves of holder member 11b, a closure will be provided which is firmly seated in the aperture 10a of carrier plate 10, with part 11a projecting from the back surface of carrier plate 10, and with part 11b projecting from the front face of carrier 10. The aperture 12 for telephone wiring 13 is preferably provided in holder part 11a so that the wiring will enter the closure for the sound translating instrumentality from the rear side of carrier plate 10.

An ear plug 14, which is preferably made of a deformable material such as rubber, is provided with a central bore 20, and ear plug 14 is provided with a rearwardly extending flange 21 adapted to be engaged over boss 18 of holder part 11b, so that, when the front portion 22 of the ear plug, which is adapted to fit into the entrance to the auditory canal of the user's ear, is inserted in the user's ear, the bore 20 of ear plug 14 will be aligned with the bore 19 of holder part 11b thus providing a sound transmitting air channel which communicates between the sound vibration translating means contained within holder 11 and the auditory canal of the user's ear.

The preferably deformable character of ear plug 14 enables it to cooperate with the bearing and sound insulating means about to be described.

Fixed to the carrier plate 10, preferably by detachable means, such for example as the means shown, and hereafter described herein, and fitting preferably snugly around the holder 11 is a closure member comprising a substantially web-like portion 23 having around its outer periphery an annular envelope 24, made of any suitable soft yieldable material, such, for example, as velour or other pile fabric. Preferably the envelope 24 is of a form such that when filled it has a rounded surface adapted for use as a bearing surface against the user's head, and of a size to wholly encompass the user's ear along its minor axis and to contact only the soft extremities of the ear along its major axis and to conform itself to the shape of the user's ear. The envelope 24 also serves to space carrier plate 10 and the web portion 23 laterally from the user's head so that a sound-insulated space is provided around the user's ear with room therein for the holder member 11b and ear plug member 14.

The envelope 24 is filled with a soft sound excluding and sound damping material 25, such, for example, as cotton or wool wadding or filling. I prefer to use for this purpose a substantially annular blank of the selected wadding material, of suitable thickness and pliancy, bent over upon itself peripherally, as by turning the outer portion 26 thereof back over one face of the blank, forming a filling member substantially U-shaped in cross section the arm 26 of which is superimposed over the arm portion 27, as illustrated in Figure 1. The arms 26 and 27 of the filling formed in this way tend to straighten out and thus expand the envelope, and this action takes place substantially all around the envelope. The bent-over portion 26, in attempting to unbend, presses outwardly against the inner face of the envelope 24, thus tending to form a tight closure against the head of the user over and around the user's ear, and also serves to space the web-like portion 23, the carrier plate 10, and the members 11 and 14, laterally from the user's head, providing a noise insulated space between carrier

plate 10 and the user's head around the members 11b and 14.

The closure member is preferably of a minimum diameter less than the maximum diameter of the carrier plate 10, and of a maximum diameter greater than the maximum diameter of carrier plate 10 so that the outer and rounded portion of said envelope has a yielding cantilever action along the major axis of the ear, and may bend backwardly to some extent over the edge of carrier plate 10, in effecting self-accommodating deformation according to the contour of the head and ear when the assembly is pressed against the user's ear. In thus self adjusting itself and the spacing of the carrier plate from the user's head the closure means cooperates and coacts with deformable ear plug 14 which is adapted to adjust itself in length in order to comfortably position the device on the user's head.

As illustrated herein the envelope 24 and web-like portion 23 are formed of a plurality of overlapping annular members, one of which, such as the facing 28, may, for example, be of velour, and the other of said annular members, which constitutes the backing member 29, may be of any strong, durable, and preferably inexpensive material, such for example as a coarse cotton fabric. The facing member 28 has its peripheral portion carried across the face of the resilient filling member 25 and around its bent-over annular portion to a point, such as x, on its rear face. The backing 29 may be superimposed over the bent-over outer edge portion of facing 28 and secured thereto, preferably adhesively, as by thermoplastic adhesive, but sewing or any other suitable means may be employed, and the facing and backing members 28 and 29 are secured together along a circular line which is spaced from their inner peripheral edge portions, as at y, thus forming the web portion 23 and the envelope 24 extending around the periphery of the web portion 23.

As illustrated herein the attachment means between the closure forming member and the carrier plate 10 is provided by the female snap members 30, carried by the flaps 31 which are secured to the back of the closure forming assembly, and the cooperating male snap fasteners 32 which are positioned and spaced at intervals around the rear face of carrier plate 10. The flaps 31 may all conveniently be related to an annular anchoring strip 33 secured to the annular backing member 29 of the closure forming assembly. The said anchoring strip 33 is secured to the closure forming assembly so that backing plate 10 may be readily inserted under the flaps 31, preferably with the inner edge of anchoring strip 33 extending over the outer peripheral edge of the backing plate.

Any suitable means may be provided for attaching the carrier plate 10 to means for positioning and holding the device on the user's head with the ear plug 14 inserted in the user's ear. As illustrated herein the carrier plate 10 is provided with two pairs of slots 34 and 35, adapted to respectively receive the ends of two straps 36 and 37 respectively, by which the device may be held on the operator's head. Another strap 38 may be provided, having at its end a female snap fastener member 39 adapted to engage the male snap member 40 on the rear face of carrier plate 10, which may be used as a chin strap to further secure the device on the user's head.

It will be noted, as illustrated in Figures 1 and 2, that the envelope 24 encloses the user's ear 41 so that no substantial pressure is exerted by the

device on the cartilages of the ear, such pressure as there is being distributed widely around the user's ear and over the soft portions thereof.

There is thus provided a noise insulated space which acts as a housing for the members 14 and 11a enabling sound impulses from the diaphragm or other sound translating instrumentality, which in this embodiment of the invention is contained in holder 11, to be communicated to the ear of the operator within a space shielded from external noises. To minimize and prevent vibrations from being set up in the assembly itself I preferably provide the carrier plate 10 and holder 11 with a thin coating of a vibration damping material, preferably a plastic material, such, for example as a bituminous material which may contain mineral filler and which may be applied by spraying it, preferably on the inside face of carrier 10, and on the inside of parts 11a and 11b of holder 11, and allowing it to harden thereon.

In the assembly as described herein a soiled or damaged closure member may be readily detached from the carrier and a new closure member substituted in place of the old one.

The closure member and particularly the bearing surface of envelope 24 may be asepticized to protect the wearer against infection. I have found that a fabric closure member has many advantages over one made of rubber since it readily absorbs disinfectant, is less susceptible to extremes of temperature, and is freer from condensation of moisture on its surface thus greatly increasing the comfort of the user.

It will thus be seen that there has been provided by this invention an apparatus, in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What I claim is:

1. A resilient annular closure member adapted to be fixed on the ear side of an earphone assembly to surround and insulate the sound-transmitting air path between the earphone assembly and the user's ear against extraneous vibrations by resilient conforming contact with the user's head, said annular closure member comprising a fabric envelope and a resilient fibrous filler mass peripherally folded on itself so as to exert an expansive force on the envelope.

2. A closure member as defined in claim 1, hav-

ing a diameter greater than the minor axis of the human ear but sufficiently small to permit resilient conforming contact near its periphery with the user's head on a line entirely surrounding the ear opening.

3. The combination comprising an earphone assembly having a carrier plate, a sound-translating means so mounted on the carrier plate as to provide a sound-transmitting air path to the user's ear when the earphone assembly is in position for use, electric conduction means for connecting the sound-translating means with signal-receiving equipment, and a resilient annular closure member so constructed and disposed as to resiliently engage and conform to the user's head when in use and to surround the sound-transmitting air path and insulate it against extraneous vibrations, the closure member comprising a fabric envelope and a resilient fibrous filler mass peripherally folded on itself so as to exert an expansive force on the envelope and prevent substantial pressure of the device on the cartilages of the ear while permitting resilient operative contact with the wearer's head, said closure member being provided with separable fastening means cooperating with complementary fastening means on the carrier plate so disposed that the closure member may be readily removed without disassembling other parts of the earphone assembly.
4. A combination as defined in claim 3, in which rigid parts of the earphone assembly are covered with a plastic vibration-damping coating.
5. A combination as defined in claim 3, in which the sound-transmitting air path is defined at least in part by the bore of a deformable tubular ear plug.
